(57) **CLAIM**

The ornamental design for a window bird feeder as shown and described.

DESCRIPTION

FIG. 1 is a front perspective view of a window bird feeder, showing my new design;

FIG. 2 is a rear perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof; and,

FIG. 8 is a bottom plan view thereof.

In the drawings, the equal-length broken lines depict portions of the window bird feeder that form no part of the claimed design. The dash-dot-dot-dash broken lines define the bounds of the claim. All broken lines form no part of the claimed design. The short-short-long dashed broken lines immediately adjacent to the claimed areas in the views represent the boundaries of the design and form no part of the claimed design.
